Patented Aug. 31, 1971

221,714

COFFEE GRINDER OR SIMILAR ARTICLE

Florian Seiffert, Schonberg, Aunus, Germany, assignor
to Braun AG, Frankfurt am Main, Germany

Filed Feb. 4, 1970, Ser. No. 21,264

Claims priority, application Germany Aug. 4, 1969

Term of patent 14 years

Int. Cl. D7—04

U.S. Cl. D89—1

FIG. 1 is a front perspective view of a coffee grinder or similar article showing my new design, with the receptacle member omitted for ease of illustration;

FIG. 2 is a right side perspective view thereof, with the receptacle in place;

FIG. 3 is a left side perspective view of FIG. 1;

FIG. 4 is a rear perspective view of FIG. 1; and

FIG. 5 is a top plan view with the cover member removed.

I claim:

The ornamental design for a coffee grinder or similar article, substantially as shown and described.
